SEAT STRUCTURE

Carl H. Oermann, York, Pa.

Application May 9, 1941, Serial No. 392,602

4 Claims. (Cl. 155—54)

This invention relates to furniture and more particularly to the seat structure of chairs, gliders, couches, benches, and the like.

An object of the invention is to provide an improved seat structure in which the back and the seat portions are formed from a single piece of thin, flexible sheet metal.

Another object of the invention is to provide an improved seat structure in which the single piece of sheet metal which constitutes the back and the seat is flexibly supported in a suitable frame.

Another object of the invention is to provide an improved seat structure in which the frame for supporting the back and the seat may be formed of a flexible tubular metal member.

Another object of the invention is to provide an improved seat structure in which the several parts are adapted to be secured together with a minimum number of attaching or holding elements.

With the foregoing and other objects and advantages in view, the invention consists in the construction and arrangement of the several parts which will be hereinafter more fully described and claimed.

In the accompanying drawings:

Figure 1 is a perspective view of a chair constructed according to the present invention;

Fig. 2 is a vertical section taken on the line 2—2 of Fig. 1; and

Fig. 3 is an enlarged rear elevation of the chair shown in Fig. 1.

Referring to the drawings, the frame for supporting the seat structure, preferably comprises a tubular metal member bent to form base bar portions 11, legs 12, and arm rests 13.

The seat 14 and the back 15 are formed from a single piece of flexible sheet metal.

The upper transverse edge of the back portion 15 is rolled or curved, as indicated at 16, and the transverse edge portion at the front of the seat 14 is likewise rolled or curved, as indicated at 17.

The upper arcuate portion 16 provides a convenient head rest at the upper edge of the back 15 for an occupant of the chair, and likewise the arcuate portion 17 provides a comfortable portion at the front edge of the seat.

Between the seat 14 and the back 15 the seat structure is formed with a curved portion 18, which is adapted to conform somewhat to the shape of the body when the chair is occupied.

The width of the sheet metal used in forming the seat 14 and the back 15 is slightly less

than the distance between the legs 12 and the arm rests 13, so that from the upper portion of the back 15 to the front portion of the seat 14, the sides of the sheet metal are free to flex or move with respect to the frame of the chair.

The rear or upper ends 119 of the arm rests 13 are bent upwardly and inwardly for attachment by bolts 20 to the back 15, as shown in Fig. 3.

In order to fasten the front of the seat 14 to the frame, a cross bar 21, which may be in the form of an angle iron, is secured to the legs 12, as indicated at 22.

The cross bar 21 is disposed at a point a suitable distance beneath the front portion of the seat 14, as shown in Figs. 2 and 3, and said bar 21 is adapted to support the front ends of a pair of leaf springs 23.

Each leaf spring 23 has a front downturned portion 24 which is secured to the bar 21 by a bolt 25. The leaf springs 23 extend in a slight arc upwardly and rearwardly and terminate at a point a suitable distance to the rear of the front edge 17 of the seat 14, that is to say, the rear ends of the leaf springs are disposed near the middle of the seat 14.

Also arranged beneath the seat 14 in substantially the same vertical plane as each leaf spring 23, is a second pair of leaf springs 26.

The front ends of the leaf springs 26 are secured to the front edge 17 of the seat 14 by bolts 27.

The leaf springs 26 are somewhat in the form of an ogee curve, in side elevation, as shown in Fig. 2, and said leaf springs 26 extend from the front edge 17 of the seat 14 rearwardly and their rear end portions underlie the rear ends of the leaf springs 23. Each pair of leaf springs 23, 26 is secured to the seat 14 by a bolt 27.

The manner in which the seat is connected to the frame of the chair is such that the seat 14 is supported from the cross bar 21 by the pair of leaf springs 23, and the front edge portion 17 of the seat is connected to the main body of the seat 14 and thereby supported therefrom, by the leaf springs 26. By thus flexibly connecting the seat 14 with the frame with the two sets of leaf springs 23 and 26, respectively, the seat structure, as a whole is made very flexible and consequently provides a structure which, although entirely constructed of metal, is more comfortable and more flexible than other metallic chair or seat structures heretofore provided.

The purpose of the leaf springs 26 is to support the front edge 17 of the seat so as to prevent ab-

55

normal distortion or flexure of said front edge when the seat is occupied.

Having thus described my invention, what I claim is:

1. Seat structure comprising a frame formed of tubular metal bent in loop form to provide a base, front legs, and arm rests, the sides of said loop being bent upwardly and inwardly at the rear extremities of the arm rests to form back supporting portions, a transverse bar fastened to the leg portions of said frame at a point beneath said arm rests, a single sheet of flexible metal forming the back and the seat of said structure, said seat extending forwardly of said transverse bar and said legs, means for securing the back portion of said flexible metal sheet to the back supporting portions of said frame, a pair of leaf springs mounted beneath the seat portion of said metal sheet and extending from an intermediate portion of said seat forwardly to said transverse bar and secured thereto, and a second pair of leaf springs of ogee form disposed in substantially the same vertical planes beneath the first pair of leaf springs and extending forwardly beneath said transverse bar and secured at their forward ends to the front portion of said seat, the leaf springs in each vertical plane being secured to the seat by a single fastening element.

2. Seat structure comprising a frame formed to provide a base, front legs, and arm rests, the sides of said frame being bent upwardly and inwardly at the rear extremities of the arm rests to form back supporting portions, a transverse bar fastened to the leg portions of said frame at a point beneath said arm rests, a single sheet of metal forming the back and the seat of said structure, said seat extending forwardly of said transverse bar and said legs, means for securing the back portion of said metal sheet to the back supporting portions, a pair of resilient elements mounted beneath the seat portion of said metal sheet and extending from an intermediate portion of said metal sheet forwardly to said transverse bar and secured thereto, and a second pair of resilient elements disposed in substantially the same vertical planes beneath the first pair of resilient elements and extending forwardly beneath said transverse bar and secured at their forward ends

to the front portion of said seat, the resilient elements in each vertical plane being secured to the seat by a single fastening element.

3. Seat structure comprising a frame formed of tubular metal bent in loop form to provide a base, front legs, and arm rests, the sides of the loop being bent upwardly and inwardly at the rear extremities of the arm rests to form back supporting portions, a cross bar fastened to the leg portions of said frame at a point beneath said arm rests, a single sheet of flexible metal forming the back and the seat of said structure, said seat extending forwardly of said cross bar, means for securing the back portion of said metal sheet to the back supporting portions, a pair of leaf springs mounted beneath the seat portion of said metal sheet and extending from an intermediate portion of said seat forwardly to said cross bar and secured thereto, and a second pair of leaf springs disposed in substantially the same vertical planes beneath the first pair of leaf springs and extending forwardly beneath said cross bar and secured at their forward ends to the front portion of said seat, the leaf springs in each vertical plane being secured to the seat by a single fastening element.

4. Seat structure comprising a frame formed to provide front legs and arm rests, the sides of said frame being shaped at the rear extremities of the arm rests to form back supporting portions, a transverse bar fastened to the leg portions of said frame, a member forming the back and the seat of said structure, said seat extending forwardly of said transverse bar, means securing the back portion of said member to the back supporting portions of said frame, a pair of resilient elements mounted beneath the seat and extending from an intermediate portion of said seat forwardly to said transverse bar and secured thereto, and a second pair of resilient elements mounted beneath the seat and disposed in substantially the same vertical planes beneath the first pair of resilient elements and extending from an intermediate portion of said seat forwardly beneath said transverse bar and secured at their forward ends to the front portion of the seat.

CARL H. OERMANN.
